UNITED STATES PATENT OFFICE.

JOHN W. BOZEMAN, OF BALTIMORE, MARYLAND.

FLUSH-TANK BULB.

1,313,161.

Specification of Letters Patent. Patented Aug. 12, 1919.

Application filed April 21, 1919. Serial No. 291,457.

To all whom it may concern:

Be it known that I, JOHN W. BOZEMAN, citizen of the United States, residing at Baltimore, State of Maryland, have invented 5 certain new and useful Improvements in Flush-Tank Bulbs; and I do declare the following to be a full, clear, and exact description of the invention, such as will enable others skilled in the art to which it applies to make and use the same.

10 My invention relates to improvements in the bulbs, commonly used as valves for the outlets of flush tanks. Heretofore, bulbs of this character that have been in general use 15 have been spherical and in time, the suction, pressure of the water, shape of the valve seat, etc., has distorted such bulbs, weakening the seat engaging surfaces thereof, and causing leakage, and when such distortion 20 takes place, the lower end of the bulb often prevents proper discharge of water from the overflow pipe of the flush tank into the bowl.

One of the foremost objects of my invention is to provide a bulb which will not be 25 distorted by continued use and which will therefore be of service for a much longer time.

A further object is to provide a bulb 30 which is applicable to practically all of the seats now in common use and one which will effectively prevent leakage regardless of the form of seat upon which it is used, the device being therefore of particular advantage for the use of plumbers in making repairs.

35 It is now necessary to carry bulbs of different sizes to meet the conditions which may be encountered, whereas carrying one of the improved bulbs will be ample, due to its adaptability to numerous sizes and shapes 40 of seats.

A still further object is to provide a bulb which will in no manner obstruct the passage of water from the overflow of the flush tank to the bowl.

45 With the foregoing in view, the invention resides in the novel construction of the bulb hereinafter described and claimed, reference being made to the accompanying drawing.

Figure 1 is a side elevation of a bulb constructed in accordance with my invention 50 showing the application thereof to one of the well known seats.

Fig. 2 is a vertical section.

Fig. 3 is an elevation of the lower end of 55 the bulb.

Figs. 4 and 5 are side elevations of the

bulb showing its application to different forms of seats.

The improved bulb is hollow as usual and consists of upper and lower halves 1 and 2 60 which are integrally joined, said upper half being provided with the usual nut or the like 3 to receive the lift rod 4, while the lower half is vented at 5 for the well known reasons.

65 The upper half 1 is of truly cone shape with the exception of its upper end which may be slightly flattened to accommodate the nut or the like 3, and said half is provided with a relatively thick side wall 6 which will yield to some extent but will at the same time be more or less rigid to prevent distortion from the pressure of the water in the flush tank.

70 The lower half 2 is in the form of an inverted cone frustum with the exception that its lower end 7 is in the form of a segment of a sphere. The wall 8 of the half 2 is relatively thin and will thus readily adapt itself to any slight irregularities in the seat.

75 By constructing the bulb in the manner shown and described, it is readily usable on practically any of the numerous types of valve seats now commonly employed. In Fig. 1, the bulb is shown upon a seat 9 having a straight bevel with which the wall 8 of the half 2 snugly contacts throughout the width of the bevel; in Fig. 4, the seat 10 is beveled and at the same time slightly concave, but the bulb fits with sufficient snugness to prevent any possibility of leakage; 80 and in Fig. 5, the seat 11 has a straight bevel but is more nearly vertical and narrower than in Fig. 1 but nevertheless the bulb seats tightly and it will not permit leakage. It 85 will be observed that the lower end 7, due to its particular shape, does not obstruct the outlet port 12 from the overflow pipe 13 and since the novel shape of the entire device prevents distortion thereof even after 90 months of use, said port will at no time be obstructed as by the bulbs now in use after distortion thereof. Not only is the shape of the lower half of the improved bulb essential, but the shape and thickened wall of the 95 upper half 1 is of paramount importance, since it prevents stretching or elongation of the bulb by the upward pull of the rod 4 against the weight of the water and the suction of the bulb against its seat.

100 From the foregoing, taken in connection with the accompanying drawing, it will be 105 110

seen that although the device is of extremely simple and inexpensive nature, it will be highly efficient on numerous types of valve seats and will be of much longer life than the bulbs now used, in addition to being free of the objections to which these bulbs are subjected. Since excellent results have been obtained from the exact construction shown, I prefer to follow such construction with the exception that any suitable device may be provided at 3 for attaching the bulb to its operating means.

I have found that the best results are obtainable when the peripheral seat engaging wall of the half 8 is located at approximately 30 degrees to the vertical axis of the bulb and when this surface is relatively wide, preferably of approximately half the height of the device. By this angular 15 position of the seat engaging surface and its unusual width I am enabled to fit any of the nine sizes and types of valve seats by manufacturing my improved bulb in only three sizes. This is of advantage to the trade in 20 numerous ways and constitutes an important 25

advance in the art, since it eliminates carrying in stock a special size bulb for each size and design of seat and does not necessitate that plumbers and others shall carry a great number of bulbs when sent out to make 30 repairs.

I claim:

The herein described one-piece rubber flush tank bulb including an upper relatively thick walled half to withstand the 35 water pressure in the flush tank and the strain in unseating the valve, and a lower inverted frusto-conical half provided with a comparatively thin wall for self adaptation to numerous sizes, curvatures and bevels of 40 valve seats in general use, the peripheral seat engaging surface of said lower half being positioned at substantially thirty degrees to the vertical axis and being relatively deep to adapt it for seating on a plu- 45 rality of different sized valve seats.

In testimony whereof I have hereunto set my hand.

JOHN W. BOZEMAN.
